(57) **CLAIM**

I claim the ornamental design for a product packaging, as shown and described.

DESCRIPTION

FIG. 1 is a perspective view of an embodiment of the product packaging;

FIG. 2 is a front view of the product packaging of FIG. 1; FIG. 3 is a rear view of the product packaging of FIG. 1; FIG. 4 is a right side view of the product packaging of FIG. 1;

FIG. 5 is a left side view of the product packaging of FIG. 1;

FIG. 6 is a top view of the product packaging of FIG. 1; and FIG. 7 is a bottom view of the product packaging of FIG. 1.

FIG. 8 is a perspective view of another embodiment of the product packaging;

FIG. 9 is a front view of the product packaging of FIG. 8; FIG. 10 is a rear view of the product packaging of FIG. 8; FIG. 11 is a side view of the product packaging of FIG. 8; FIG. 12 is a side view of the product packaging of FIG. 8; FIG. 13 is a top view of the product packaging of FIG. 8; and FIG. 14 is a bottom view of the product packaging of FIG. 8.

FIG. 15 is a perspective view of another embodiment of the product packaging;

FIG. 16 is a front view of the product packaging of FIG. 15; FIG. 17 is a rear view of the product packaging of FIG. 15; FIG. 18 is a side view of the product packaging of FIG. 15; FIG. 19 is a side view of the product packaging of FIG. 15; FIG. 20 is a top view of the product packaging of FIG. 15; and

FIG. 21 is a bottom view of the product packaging of FIG. 15.

FIG. 22 is a perspective view of another embodiment of the product packaging;

FIG. 23 is a front view of the product packaging of FIG. 22; FIG. 24 is a rear view of the product packaging of FIG. 22; FIG. 25 is a side view of the product packaging of FIG. 22; FIG. 26 is a side view of the product packaging of FIG. 22;

(Continued)

FIG. 27 is a top view of the product packaging of FIG. 22; and, FIG. 28 is a bottom view of the product packaging of FIG. 22.

The broken lines in the drawings illustrate features of the product packaging or the environment in which the product packaging is used, which form no part of the claimed design.

1 Claim, 28 Drawing Sheets
